UNITED STATES PATENT OFFICE.

ISIDORE THERRIEN, OF QUEBEC, QUEBEC, CANADA.

SMOKE-CONSUMING APPARATUS.

1,279,939.

Specification of Letters Patent. Patented Sept. 24, 1918.

Application filed March 12, 1917. Serial No. 154,197.

To all whom it may concern:

Be it known that I, ISIDORE THERRIEN, a subject of the King of Great Britain, and residing at 115 Commissioner street, in the 5 city of Quebec, in the Province of Quebec, in the Dominion of Canada, have invented certain new and useful Improvements in a Smoke - Consuming Apparatus; and I do hereby declare that the following is a full, 10 clear, and exact description of the same.

The invention relates to improvements in "smoke consuming furnaces" and consists especially of a novel arrangement of a plurality of draft conductors longitudinally disposed within the fire box.

The object of the invention is to devise a furnace of the character described, in which the oxygen will be suitably proportioned in relation to the carbon and hydrogen escaping from the fuel in combustion.

In all furnaces in which soft coal is used, it is practically impossible to obtain satisfactory results with smoke consumers without proportioning the quantities of oxygen 25 and fuel gases. The air or draft which is blown below the grate arrives on the surface of the fire with a minimum proportion of oxygen and thus oxidizes the hydrogen, which is one of the elements composing the 30 carburets which are very numerous on the surface of the fire, and the pure carbon escapes in the form of smoke. So, in order that combustion may be complete, the air must oxidize all the hydrogen carburets and 35 must transform the carbon into CO_2 .

In order to attain this result, a special form of furnace must be devised. The invention is better explained by reference to the drawings, in which Figure 1 is a perspective view of the invention secured between the bridge wall of a furnace and the front wall, the side walls being eliminated from the drawings.

Fig. 2 is an enlarged perspective view of 45 one of the draft conductors, a portion of the upper part being shown in section in order to disclose the peculiar arrangement of the draft conduits.

Fig. 3 is a front elevation of a portion of 50 a furnace, showing the draft conductor and the different doors closing the entrance to each section.

Fig. 4 is a perspective view of the draft conductors, the fire box having been removed.

Fig. 5 is a longitudinal sectional view through the furnace.

Fig. 6 is a cross section through one of the draft conductors.

Like numerals of reference indicates corresponding parts in each figure.

The device consists of an ordinary boiler furnace having side walls 1 and 2, a front wall 3 and a back wall which is not shown, and 4 is a bridge wall secured within the 65 furnace. 5 is the ash pit, and 6 is the ash pit door.

7 are doors in the front wall of said furnace, suitably hinged, and here shown as being four in number. It may here be mentioned that one door could probably be used just as well as four or five doors; this will depend on the size of the furnace. These doors do not form part of the invention.

8 is the draft conductor, composed of a 75 wide base 9 and an upwardly projecting member 10, here shown as having a V-shaped head 11. The said draft conductor 8 is preferably of the length of the fire box and may be secured on the cross beam 12 80 at one end. The other end of the said draft conductor is here illustrated as having an outwardly projecting arm 13 which is adapted to be secured in the masonry of the bridge wall of the furnace.

85 14 are cross beams adapted to be supported by said wide base 9. These cross beams 14 are preferably disposed with short spaces between them and are adapted to support the fire bricks which are laid in between 90 the said draft conductors 8 and form a flooring as illustrated in Fig. 1.

16 are vertical transverse channels across the member 10 and preferably perpendicular in relation to the said member 10 and parallel to one another. Said channels have preferably, intermediate of their width, enlarged portions 17 which extend through the bottom of said base member 9 and form 95 communicating passages between the ash pit 100 and the fire pot.

These passages are disposed laterally, and the particular shape of the channels 16 will cause the draft which rushes through the enlarged portions 17 to blow with increased 105 velocity through the said openings 16 into the mass of fuel in combustion at the very spot where the carburets and hydrogen are located, thus oxidizing said carburets and hydrogen.

It will thus be seen that the combustible gases and carbon will be oxidized, while the forced air still has a sufficient amount of oxygen so that there will be no smoke, and 5 only the non-combustible gases, which are colorless, will then escape from the furnace.

The forward part of the fire box between the sections which are formed of fire bricks, is illustrated in Fig. 1 as having an inclined 10 surface toward the front, in order to facilitate the taking-out of cinders and clinkers. Each door 7 preferably corresponds to one of the fire pots formed by the members 8, and the cinders may be scraped out through 15 the said doors or may fall through the channels 16 into the ash pit 5.

The pipe 18 communicates with the ash pit and is preferably connected at the other end to a blower in order to force air into the 20 pit and through the channels 16.

In Fig. 6 is illustrated a cross-sectional view through one of the draft conductors, and particular attention is called to the V-shaped top 11 of the conductor. This V-shaped top has the advantage of properly 25 directing the forced air.

What I claim is:—

1. A smoke consuming furnace of the character described, comprising a plurality

of draft conducting members disposed within the fire box, said members having V-shaped tops and being provided with a plurality of parallel vertical air channels which are enlarged intermediate of their width, said air channels communicating at their 25 sides with the combustion zone and at their lower ends with the ash pit of said furnace; and air-tight flooring between said members to support the fuel, substantially as described.

2. A furnace of the character described, comprising a plurality of parallel draft conducting members secured within the fire box, each member having an outwardly projecting longitudinal flange on each side and also having a plurality of vertical air channels communicating at their sides with the combustion zone and at their lower ends with the ash pit; cross beams between said 45 members, resting on said flanges; and an air-tight flooring on said beams, substantially as described.

Signed at Quebec, Canada, this twenty-fourth day of February, 1917.

ISIDORE THERRIEN.
